(57) **CLAIM**

The ornamental design for a handle for a valve, as shown and described.

DESCRIPTION

FIG. 1 is a top, right perspective view of a handle for a valve, showing my design.

FIG. 2 is a top plan view thereof;

FIG. 3 is a bottom plan view thereof;

FIG. 4 is a front elevational view thereof, the rear, left and right elevational views being the same due to symmetry;

FIG. 5 is a bottom, right perspective view thereof;

FIG. 6 is a bottom, left perspective view thereof; and,

FIG. 7 is a top, left perspective view thereof.
